UNITED STATES PATENT OFFICE.

EDITH M. SHAWE, OF HUNTINGTON, NEW YORK.

DESIGN FOR A DOLL.

61,052.

Specification for Design.

Patented June 6, 1922.

Application filed January 21, 1922. Serial No. 300. Term of patent 7 years.

To all whom it may concern:

Be it known that I, EDITH M. SHAWE, a citizen of the United States, and residing at Huntington, county of Suffolk, State of New York, have invented a new, original, and ornamental Design for Dolls, of which the following is a specification, reference being had to the accompanying sheet of drawings, forming a part thereof.

In the drawings, Fig. 1 is a front view of a mother doll embodying the design in a preferred form thereof. Fig. 2 is a rear view of the doll shown in Fig. 1.

I claim:

The ornamental design for a doll substantially as shown.

EDITH M. SHAWE.
